UNITED STATES PATENT OFFICE.

NELSON SAWYER, OF CLEVELAND, OHIO.

DIE-STOCK.

SPECIFICATION forming part of Letters Patent No. 730,166, dated June 2, 1903.

Application filed November 1, 1902. Serial No. 129,658. (No model.)

To all whom it may concern:

Be it known that I, NELSON SAWYER, a citizen of the United States, residing at Cleveland, in the county of Cuyahoga and State of Ohio, have invented a certain new and useful Improvement in Die-Stocks, of which the following is a full, clear, and exact description, reference being had to the accompanying drawings.

The object of my invention is to provide a die-stock having a head which is recessed to receive a member hinged thereto, with suitable means for adjusting the relative position of said hinged member and also with means for locking them together in any adjusted position.

It is a further object of my invention to provide a suitable latch for the dies.

The invention is fully disclosed in the following description and claim, and illustrated in the drawings.

Referring to the drawings, Figure 1 is a top plan view of my device. Fig. 2 is a side elevation. Fig. 3 is a bottom plan. Fig. 4 is a horizontal section taken on the line 4 4 of Fig. 2 and showing the dies in place. Fig. 5 is a cross-section on line 5 5 of Fig. 1. Fig. 6 is a section on line 6 6 of Fig. 1, and Fig. 7 is a detail view in section, showing the die and the latch therefor.

Referring to the parts by letters, A' represents the head of the die-stock, having a member pivoted thereto at A² and occupying a recess in one end of the head. An adjusting-screw a², mounted in the head, is adapted to engage a shoulder a³ on the hinged member A of the stock. One handle, B, is screwed through the handle-socket a', which has a conical end b, adapted to engage a conical recess a⁵ in the end of the hinged member A of the stock. Another handle, B', is secured to the opposite side of the head, preferably in another handle-socket a. When the stock is being closed, the member A is swung upon its pivot until the shoulder a³ abuts against the adjusting-screw a², and the handle B is then screwed into the handle-socket a' until the conical end b engages in the conical recess a⁵, thereby firmly locking the member A of the stock to the head A' and against the adjustable set-screw a².

The head A' and the hinged member A of the stock are provided with radial recesses C, in which the dies D are adapted to slide. These dies are substantially of the form shown 55 in Fig. 5, having cutting-teeth d on their inner ends and a cut-away portion d' at the top and near the back end, whereby they may pass under the retaining-plates F' and a cross-notch d² in such cut-away portion for 60 the purpose of being engaged by a latch which will retain the dies in place in the stock. Each one of the dies D is secured within its recess C against endwise movement by means of a latch E. This latch consists of a thumb-piece e, a squared shank e', which projects through a circumferential slot F in a retaining-plate F', and has on the lower end thereof a boss e² for engaging in the notch d² of the die. The plates F' are semicircular in form 70 and are placed upon the stock, as shown, and are secured thereto by means of screws f.

The latches E operate in the following manner: If dies are already in the stock, the boss e² of each latch is in engagement with the recess d² of each die. When the dies are to be removed, the thumb is placed upon one of the thumb-pieces and the latch in connection therewith is moved until the boss e² passes out of the notch d² of each die, when the die 80 will be free to slide from its recess. This operation is continued in connection with each die. If other dies are to be inserted, they are taken individually and passed into a recess, being pushed in as far as they will go. 85 Then the latch is moved toward the die, thus carrying the boss e² into engagement with the recess d².

On the under side of the stock is arranged a suitable guiding mechanism for the pipe to 90 be threaded, which consists of the jaws G, adapted to slide in suitable openings in the stock and having pins g, which engage cam-slots h in an operative ring H. This ring is retained in proper position by means of an 95 other ring K, which is secured to the stock by means of screws k.

A thumb-piece M may be provided upon the hinged member A of the stock for swinging the same upon its pivot.

Having described my invention, I claim—
In a die-stock consisting of a head having a

suitable recess therein adapted to receive a hinged member and having also an internally-threaded tubular handle-socket, a member hinged to said head and having a conical recess in its free end, a handle screwed into said socket, and having a conical inner end for engaging the recess in the end of said hinged member and an adjusting-screw mounted in said head for engagement with

10 said hinged member, substantially as and for the purpose specified.

In testimony whereof I hereunto affix my signature in the presence of two witnesses.

NELSON SAWYER.
